Attorneys.

UNITED STATES PATENT OFFICE

SAMUEL SEGAL, OF NEW YORK, N. Y., ASSIGNOR TO SEGAL LOCK & HARDWARE CO., INC.,
OF NEW YORK, N. Y., A CORPORATION OF NEW YORK

RAZOR

Application filed May 11, 1928. Serial No. 276,910.

This invention relates to a razor and specifically, a safety razor incorporating functionally and structurally improved features.

It is an object of the invention to furnish a device of this character, the parts of which, will be relatively few in number and individually simple and rugged in construction, these parts being capable of being manufactured and assembled readily so that a razor 10 may be produced which will sell at a relatively nominal figure and which will give satisfactory service free from any mechanical difficulties.

A further object of the invention is that of 15 constructing a razor in which the guard may be somewhat permanently associated with the blade so that the danger of a person cutting themselves will be reduced to a minimum.

20 A still further object is that of furnishing such an article in which the position of the blade may be adjusted readily in order that the razor may be used advantageously in connection with different types of beards.

25 With these and additional objects in mind, reference is had to the annexed specification and attached drawings, which latter present one practical embodiment of the invention and in which:—

30 Figures 1 and 2 are bottom plan and side views respectively of a razor and showing the parts thereof in one position;

Figs. 3 and 4 are similar views showing the parts in a second position;

35 Fig. 5 is a plan view of the blade;

Fig. 6 is a perspective view of the razor, and

Fig. 7 is an enlarged fragmentary view of the razor handle, or grip.

40 In these views the numeral 10 indicates the stem which provides the razor handle and the exterior surface of which may be knurled in order that a firm grip may be assured. The outer end of this stem terminates,

45 as in Fig. 7, in a screw-threaded extension 11 having a tapered or convexed outer portion 12, the purpose of which will be herein-after brought out. Also, preferably adjacent the base of the extension 11 the stem may

50 have a spaced, concentrically disposed flange

13, the edge of which extends into a plane preferably beyond the inner end of the screw thread.

A blade is employed which may conveniently include a body 14 having a cutting edge 15 and being formed with two main openings 16—17 and an additional perforation or indentation 18 if the latter is necessary. A guard and blade-holder is provided preferably by employing sheet metal which is stamped or otherwise suitably formed to furnish an element U-shaped in cross-section, having one of its outer edges terminating in a comb 19 and the arms of said element being formed with aligned pairs of perforations 20—21. A slot 22 may also be formed in one of the arms of this element, which slot, when the blade is in position within the holder, will align with the opening or indentation 18.

It will be noted that the openings 16—17 have a diameter substantially equal to the maximum diameter of the extension 11 and the openings 20—21 have such diameter that they will engage within the base of the threaded form of this extension. Also, the distance between the openings 16—17 and 20—21 is unequal. In the present instance the distance between the former pair of openings is less than between the latter pair. Accordingly, the user of this device desiring, for example, a close shave, inserts the rounded or tapered end portion of the extension 11 within the opening 20. If the blade is, at that time, in the position shown in Fig. 1, it will be obvious that this action will cause the blade to be projected and a rotation of the stem handle with respect to the guard will cause the threads of the extension to grip the guard element and clamp the same as in Fig. 4, in which all parts are held against relative movement. If, on the other hand, it is desired to not resort to a close shave the extension of the handle is introduced through the rear opening of the handle 21, resulting in a camming action between the blade and extension of the stem and a retraction of the former within the holder, as has been shown in Figs. 1 and 2.

Due to the flange portion 13 preferably

incorporated in the handle, and also having in mind that the guard is preferably of comparatively thin metal stock, it will be obvious that a very firm clamping action is assured for the reason that the guard immediately adjacent the openings or perforations formed therein will tend to become slightly distorted resulting in a binding of the blade and guard.

10 The purpose of the opening or indentation 18 will now become apparent in that, if the user desires to strop the blade, to which end the latter must be materially projected beyond the guard or probably entirely removed therefrom, it is obvious that by the structure devised a pointed instrument may be employed to achieve the result desired. Moreover, an equivalent structure may be furnished by simply deepening one of the 20 recesses between adjacent teeth of the comb and form the blade with a perforation at this point, as has been indicated at 23 in Fig. 1, it being thus unnecessary to provide the slot 22 and opening or indentation 18. It will be 25 apparent that in order to retain the parts of the guard and the blade in proper relative positions, the side edges of the guard element may be downturned as at 24 so as to furnish rigidifying guide and blade-confining portions at this point.

From the foregoing it will be apparent that, among others, the several objects specifically aforementioned are achieved. It is to be noted, however, that numerous 25 changes in construction and rearrangement of the parts might be resorted to without in the slightest departing from the spirit of the invention as defined by the claims.

Having described my invention, what I 40 claim as new and desire to secure by Letters Patent is:—

1. A razor including a guard formed with a plurality of openings, a blade associated with said guard and formed with openings offset with respect to said guard openings and means for introduction into one of said guard openings to align the same with a blade opening to shift said blade with respect to said guard.

50 2. A razor including a guard formed with a plurality of openings, a blade associated with said guard and formed with openings offset with respect to said guard openings, a handle member and means associated with 55 said member for insertion into one of said group of openings to shift said blade with respect to said guard.

3. A razor including a guard formed with a plurality of openings, a blade associated 60 with said guard and formed with openings offset with respect to said first named openings, a handle and a projection at the end of said handle and formed with cam surface to engage the edges of said openings and to 65 align one group of the same to positively

shift said blade with respect to said guard.

4. A razor including a guard formed with a plurality of openings, a blade associated with said guard and formed with openings offset with respect to said first named openings, a handle and a projection at the end of said handle and formed with a cam surface to engage the edges of said openings and to align one group of the same to positively shift said blade with respect to said guard, and means associated with said handle to bear inwardly against said guard and tend to distort the same into clamping contact with said blade.

5. A razor including a guard formed with openings, a blade associated with said guard and formed with openings of a diameter greater than said guard openings, such blade openings being offset with respect to said guard openings, a handle, a screw-threaded extension forming a part of the same, the exterior circumference of said threads being substantially equal to the circumference of the blade openings and the circumference of the base of said threads being substantially equal to the circumference of the guard openings, whereby, upon said extension being inserted through one of said guard openings the blade opening adjacent the same will be brought to extend concentrically with respect to the guard openings and said blade will be positively shifted with respect to said guard.

6. A razor including a holder, a blade slidably disposed within said holder, a handle formed with an extension, said blade and holder having a plurality of openings, one set or such openings being non aligned when the other opening set is aligned and one opening set receiving said extension whereby to automatically shift said blade within said holder upon the extension of said handle being applied to the different openings thereof.

7. A razor including a guard formed with a plurality of openings. A blade associated with said guard and formed with openings offset with respect to said guard openings, a handle member and means associated with said member for insertion into one of said group of openings to shift said blade with respect to said guard and a slot located adjacent said guard openings whereby access is had to the blade for removing the same from the guard.

In testimony whereof I affix my signature.

SAMUEL SEGAL.
